UNITED STATES PATENT OFFICE.

CHARLES B. HOPKINS AND THOMAS H. ELSOM, OF SPOKANE, WASHINGTON.

COIN-CONTROLLED TELEPHONE.

SPECIFICATION forming part of Letters Patent No. 542,679, dated July 16, 1895.

Application filed March 16, 1894. Serial No. 503,866. (No model.)

To all whom it may concern:

Be it known that we, CHARLES B. HOPKINS and THOMAS H. ELSOM, citizens of the United States, residing at Spokane, in the county of Spokane and State of Washington, have invented a certain new and useful Improvement 5 in Coin - Controlled Telephone Apparatus, (Case No. 2,) of which the following is a full, clear, concise, and exact description, reference being had to the accompanying drawings, forming a part of this specification.

Our invention relates to coin - controlled telephone apparatus; and its object is to provide means whereby access to the telephone 15 of a pay-station may be secured by the insertion of a coin, and, further, to provide means whereby spurious coin or slugs, when inserted, will be incapable of operating the apparatus.

20 Our invention in its preferred form comprises a passage-way for the coin of some considerable length, the coin being adapted on its entrance upon the passage-way to close an electric circuit, and upon its passage therefrom to again open the circuit, thus actuating a call device and informing the operator that a connection is desired.

In order to render the apparatus inoperative under the influence of spurious coin or 25 slugs we provide a series of guideways through which the coin must pass before reaching the signal-controlling passage-way, the several guideways subjecting the coin to a series of tests and rejecting it if it does not 30 meet the requirements. Slugs composed of magnetic material are stopped in their passage by means of a magnet and removed from the guideway by the act of inserting another coin. To detect coins of inferior resiliency, 35 such as coins made of or containing considerable lead, a block of metal, as steel, is provided, against which the coin in its passage must strike, the block being so situated that a coin of inferior resiliency will fall short of 40 the next section of the guideway, and thus be rejected. To detect coins of less diameter than that of coins required to operate the apparatus the plane of the passage-way is rendered oblique for a short length, the side of 45 the way toward which the coin leans in passing this portion being cut away to permit such coins of less diameter to fall out. To reject

coins of less than the required thickness the guideway is provided for a portion of its length with a slot in the bottom of such width 55 that coins of lesser thickness will pass through the slot on arrival at this portion of the guideway. This embodiment of our invention will be more readily understood by reference to the accompanying drawings, in which— 60

Figure 1 is an elevational view of the coin-controlled apparatus. Fig. 2 is a detail view of the device for ejecting a magnetic slug. Fig. 3 is a detail view of the device for ejecting coins of inferior resiliency. Fig. 4 is a 65 transverse view of the passage-way on line 4 4, Fig. 1. Fig. 5 is a detail view showing the slot for rejecting thin coin, which is located in the bottom of the guideway. Fig. 6 is a transverse view on line 6 6, Fig. 5. Fig. 7 is 70 a view of the signal-controlling passage-way with a coin passing therethrough. Fig. 8 is a sectional view of a transmitter-mouthpiece provided with a buzzer after the manner of our invention. Fig. 9 is a sectional view on line 9 9, Fig. 8. Fig. 10 is a perspective view of a telephone set used in connection with our coin-controlled apparatus. 75

Like letters refer to like parts in the several figures. 80

The signal-controlling passage-way a comprises a zigzag path composed of oblique ways sloping alternately in opposite directions, the ends overlapping so that the coin may pass from one to another in its journey. 85 The coin in entering upon this passage-way serves to close an electric circuit to actuate the signal device and to open the circuit upon passing therefrom. The closing of the circuit is accomplished by means of the trigger 90 b', which is composed of an arm carried upon the pivoted block b, the block being so weighted that the trigger b' normally rests in the path of the coin. Upon the said block b is carried an insulating-strip b², against which 95 normally bears an arm c' of a second pivoted block c, which is so weighted that said arm is yieldingly held against said strip b². Just below the strip b² is provided a shoulder b³ upon the block b, and when the trigger b' is 100 depressed by the impact of the coin the block b is rotated until the end of arm c' rests against the shoulder b³, the block being thus prevented from rotating back to its former

position. The blocks *b* and *c* form the terminals of the electric circuit, and so long as arm *c'* rests against insulating-strip *b*² the circuit is open; but when the coin rotates block *b* the 5 metallic portions of the blocks are brought into contact to close the circuit and maintain it closed until the block *c* is caused to release the block *b*. To accomplish this release a second trigger *d'* is provided at the lower end 10 of the passage-way and consists of an arm provided upon the pivoted block *d*, which is so weighted that trigger *d'* normally rests in front of the exit end of the passage-way. When the coin strikes said trigger *d'*, block *c* 15 is rotated by means of the connecting-link *c*², thus carrying arm *c'* to the right and out of engagement with the shoulder *b*³ upon block *b*, thereby permitting block *b* to rotate to its normal position. The coin having passed the 20 trigger *d'* said trigger returns to its normal position, thus bringing arm *c'* against the strip of insulation *b*². Thus so long as the coin is on its journey through the passage-way the electric circuit is closed and may 25 serve to actuate any preferred form of signal device.

In Figs. 8 and 9 we have illustrated a signal device comprising a buzzer adapted to be placed near the diaphragm of the transmitter, 30 and to prevent its interference with the use of the transmitter for conversational purposes a receptacle is provided communicating with the mouthpiece, in which the buzzer or bell may be located. As the coin passes through 35 the zigzag passage-way it makes a characteristic noise as it falls from one way to another, and we may rely upon this characteristic sound as a signal, the transmitter, through the agency of the back board of the telephone 40 set acting as a sounding-board, transmitting the sound to the operator at the central station. Instead of using the transmitter for conveying the signal the circuit when closed 45 may actuate a signal device located at the central office or may serve in any preferred manner to inform the operator that a connection is desired.

To render the apparatus inoperative under the influence of a coin or slug possessing magnetic properties, we provide a magnet *e* with 50 its pole situated near the guideway at some point. When the magnetic slug reaches a position opposite the pole of the magnet it is stopped by the attraction of the magnet. To 55 eject the slug thus detained in its passage, the section *e'* of the guideway is rotatably mounted at *e*². A portion of the bottom of the guideway is cut away, and a rotatably mounted plate *e*³ normally serves as the 60 bottom of the guideway. When, however, the section *e'* is rotated the plate *e*³ is rotated into the position shown in Fig. 2 to form a spout, through which the magnetic slug, having 65 been removed from the influence of the magnet by the rotation of section *e'*, will pass, being thus ejected from the guideway. The section *e'* is rotated by means of a handle *e*⁴

extending through and moving in the slot *e*⁵ provided for the insertion of the coin. A plate *e*⁶ maintains the slot closed except when 70 the handle is depressed. When the handle is depressed the coin may be inserted and when released the spring *e*⁷ brings section *e'* back to its normal oblique position and causes the coin to roll through the guideway. The coin 75 having passed the section *e'* of the guideway enters the section *g*, which slants in the opposite direction. The coin upon emerging from the end of section *g* strikes the block *g'* at an angle, being deflected and bounding 80 into the section *h*. The block may be made of steel or any material possessing resiliency. The end of section *h* is located at such a distance from block *g'* that a coin of inferior resiliency will fall short of said section *h*. 85

The plane of section *h* is oblique for a portion of its length, the coin as it passes therethrough being caused to lean outward. The side toward which the coin leans is cut away at this point, so that any coin of less than the 90 required diameter will fall from the guideway through the opening *h'* in passing this portion of section *h*. At the lower end of section *h* is provided a slot *h*² in the bottom of the guideway of such a width that coins of 95 lesser thickness will, on reaching this portion of the guideway, pass through, being thus ejected from the way. The section *h* conducts the coin into section *i*, between the lower end of which and the signal-controlling 100 passage-way is located the trigger *b'*. Guide-plates *k* are provided for properly directing the rejected coins and conveying them to the coin receptacle *l*.

The operation of the device will be readily 105 understood. By depressing the handle *e*⁴ the coin may be inserted in the slot. When the handle is released the section *e'* assumes its normally-inclined position and the coin begins its journey. If of not too great diameter 110 the coin passes onward, but if magnetic it is stopped by magnet *e*, and upon depressing the handle is ejected through spout *e*³. If the coin is not magnetic it passes upon section *g* and, striking the block *g'*, bounds into 115 section *h*. If of inferior resiliency the coin falls short of section *h* and is thus rejected. Passing upon section *h* the coin is caused to lean toward the opening *h'*, and if of less diameter than that of the proper coin it will 120 pass from the way. Continuing, the coin next reaches the slot *h*², and if of less thickness than the required coin passes therethrough. Continuing, the coin reaches section *i*, and passes thence upon the signal-controlling 125 passage-way, first striking trigger *b'* and closing the circuit. The time required for the coin to complete its travel through this passage-way is sufficient to give the signal for the necessary length of time. Upon issuing from 130 this passage-way the trigger *d'* is operated to open the circuit. When the noise of the coin in passing through the signal-controlling passage-way is to be used for conveying the sig-

nal, the circuit-controlling apparatus may, of course, be omitted.

Many modifications of our invention will readily suggest themselves, and we do not, therefore, desire to limit ourselves to details; but

We claim as new and desire to secure by Letters Patent—

1. In a coin controlled apparatus, the combination with the pivoted guide way e' , yieldingly held in an inclined position, of the magnet for arresting a magnetic slug in its travel, and the pivoted plate e^3 normally forming part of the bottom of said guide way, and

15 adapted, when the guide way occupies its alternate position to form a spout for the ejection of the slug, substantially as described.

2. In a coin-controlled apparatus, the combination with the pivoted section e' , the entrance end thereof being elevated, of means for lowering said entrance end to permit the insertion of a coin, and a stationary plate extending through the bottom of said entrance end and of a height to prevent the entrance 25 of a coin of greater than the predetermined diameter; whereby such coin upon depressing said entrance end will be ejected, substantially as described.

3. In a coin controlled telephone apparatus, the combination with the signal controlling passage way a , of the circuit closing blocks b and c actuated by triggers b' and d' , the guide way e' and magnet e for ejecting mag-

netic coins, the block g' for ejecting coins of inferior resiliency, the obliquely situated 35 guide way provided with opening h' , and the guide way provided with the slot h^2 , substantially as described.

4. In a coin-controlled apparatus, the combination with a passageway through which 40 the coin is adapted to pass, of a circuit closer at the entrance to said passageway adapted to be actuated to close an electric circuit as the coin passes the same, and a circuit opener adapted to be actuated to open said circuit 45 as the coin passes the same, substantially as described.

5. In a coin-controlled telephone apparatus the combination with a buzzer situated in proximity to the telephone transmitter and 50 included in an electric circuit, of a passage-way through which the coin is adapted to pass, a circuit closer at the entrance to said passageway adapted to be actuated to close said circuit as the coin passes the same, and 55 a circuit opener adapted to be actuated to open said circuit as the coin passes the same; substantially as described.

In witness whereof we hereunto subscribe our names this 16th day of February, A. D. 60 1894.

CHARLES B. HOPKINS.
